UNITED STATES PATENT OFFICE.

BELVIN T. WILLISTON, OF SOMERVILLE, MASSACHUSETTS, ASSIGNOR TO MANNING, MAXWELL & MOORE, INC., OF NEW YORK, N. Y., A CORPORATION OF NEW JERSEY.

FEED-WATER STRAINER FOR LOCOMOTIVES.

Application filed July 25, 1924, Serial No. 728,144. Renewed November 7, 1925.

To all whom it may concern:

Be it known that I, BELVIN T. WILLISTON, a citizen of the United States of America, and resident of Somerville, in the county of 5 Middlesex and State of Massachusetts, have invented new and useful Improvements in Feed-Water Strainers for Locomotives, of which the following is a specification.

This invention relates to strainers such as 10 are used to strain the feed water injected into locomotive boilers, such strainers being interposed in the pipe leading from the tender tank to the injector and commonly comprising a housing having separable 15 parts enclosing a foraminous or perforated screen or grid.

The parts of the strainer housing are commonly held together by means of a series of 20 bolts and nuts which must be removed to gain access to the screen for cleaning it. As the strainer is located directly over the road-bed it frequently happens that the connecting bolts and nuts, after removal are dropped or mislaid and lost, while the time 25 and trouble involved in the removal and replacement of so many parts often induces neglect of the cleaning operation.

One of the housing sections is commonly secured to the end of a flexible hose leading 30 from the tender tank and when the housing sections are uncoupled this flexibly supported section is usually permitted to drop onto the ground. As its surfaces are wet it picks up sand and grit which is thus carried 35 into the feed water when the parts are replaced, while any sand which may be caught by the opposed surfaces of the sections when again united tends to produce an imperfect joint with consequent leakage.

Moreover if the screen is positioned 40 merely by being clamped by the opposed faces of the housing sections it also is liable to be dropped out onto the road-bed when the sections are uncoupled, sometimes resulting in damage or loss, and its proper replacement requires considerable care and attention.

Principal objects of the invention are to 50 provide a strainer of this type having separable housing sections enclosing a screen or grid in which the housing sections are clamped together by means of a single pressure applying device which is permanently secured to one of the housing sections so 55 that it cannot readily be misplaced or lost,

and by means of which the parts may quickly be clamped firmly together or with the same facility loosened for separation; to provide means for temporarily supporting the hose-carried section of the housing, 60 such supporting means, however, being adapted automatically to release said section if the engine and tender are uncoupled and separated; to provide means which securely retains the screen or grid in operative position relative to one of the sections of the housing even after removal of the other section but which permits the ready removal and replacement of the screen; and to embody the above features in a device of simple 70 and sturdy character containing a minimum number of parts.

In the accompanying drawings a preferred embodiment of the invention is shown by way of example,

Fig. 1 being a plan view of the improved strainer, certain parts being shown in section; and

Fig. 2 being a vertical section substantially on the line 2—2 of Fig. 1.

In the drawing the letter A designates the inlet section of the strainer housing or casing; while B indicates the outlet section of such housing or casing. These sections are hollow and complementary to each other, the section A being provided with an externally corrugated tubular portion 1 to which the end of the hose H leading from the tender tank is attached. The section B is provided with an internally screw threaded opening 2 for attachment to the pipe, not shown, leading to the locomotive injector. The section B is supported in the usual manner by means of a rigid bracket 2^a depending from the locomotive frame.

The opposed surfaces of the sections A and B are preferably provided with interfitting parts, the section B having a flange 3 which fits within a groove 4 in the opposed face of the section A. This groove 4 preferably holds a packing ring 5 of any suitable material adapted to make a tight joint between the parts.

For clamping the parts together in operative relationship a bail-like member 6 is provided. This member comprises spaced legs 6^a and 6^b having aligned openings near their ends which receive the trunnions 7 projecting from diametrically opposite sides of the section B. The legs 6^a and 6^b are united

to form the head 6^c which is provided with an internally screw threaded bore for the reception of the clamping bolt 8. The rear part of the section A is furnished with a 5 thickened portion or boss 9 preferably provided with a recess 9^a in which a wear resistant plate 9^b is seated. A curved horn or hook 10 projects upwardly from the edge of the section A for supporting the section 10 temporarily when unclamped from section B, as hereinafter described.

The section B is furnished with an annular groove 11 just inside the flange 3 and this groove receives a screen or grid 12. 15 This screen or grid is of circular contour and preferably of a diameter slightly less than that of the groove 11. The outer wall 11^a of the groove is cut away to permit the introduction of the screen or grid when disposed coaxially with the groove, while the rear wall 11^b of the groove is of such depth as to prevent escape of the screen. The screen is provided with finger pieces 13 by 20 which it may be picked up and advanced 25 axially into the groove. After entering the groove the screen may be dropped into the lower part of the groove where it remains securely held until again lifted for removal.

When in use the parts normally occupy 30 the position shown in Fig. 2, wherein the screen 12 is seated in the groove 11 and sections A and B are securely clamped together by engagement of the inner end of the bolt 8 with the wear plate 9^b. The bolt 8 may, 35 if desired, be provided with a lock nut 8^a for securing it in adjusted position.

When the screen is to be removed for 40 cleaning the bolt 8 is retracted and the bail 6 is swung upwardly to permit the section A to be dropped away from the section B to the dotted line position indicated in Fig. 2. As soon as the parts are free the bail is 45 permitted to swing downwardly and when in this position forms a support for section A, the horn 10 resting upon the inner face of the head 6^c of the bail. While the horn rests upon the surface of the bail and thus 50 supports the section A and normally prevents it from dropping onto the road-bed, the engagement of the parts is not positive 55 so that if the tender be uncoupled from the engine and moved away, the horn 10 will automatically release itself from the bail and the hose section will not be broken.

After separation of the sections of the 60 housing the screen may readily be removed and cleaned and then dropped back into position where it is securely held while the section A is being replaced. For clamping 65 the parts together the bail is replaced in the position shown in Fig. 2 and the bolt 8 is set up against the wear plate 9^b until the desired clamping pressure is obtained.

With this simple construction the objects 65 of the invention are attained in a highly

efficient manner while the construction is such that many of the parts may be of standard type and the device in general is relatively cheap to construct.

I claim:

1. A strainer comprising a casing having separable sections, a member on one section movable to engage the other section for securing said sections together, one of said sections being provided with an internal groove, and a screen or grid loosely mounted in said groove and removable therefrom after said sections have been separated by successive diametral and axial movements.

2. A strainer comprising a casing having separable sections, means for securing said sections together in fluid-tight relation, one of said sections being provided with an annular recess, and a screen or grid of a smaller diameter than the diameter of said recess normally arranged in said recess, the grid being removable from the casing after said sections have been separated by movement transversely to clear the outer wall of the recess and subsequent axial movement.

3. A strainer comprising a casing having separable sections, means for securing said sections together in fluid-tight relation, an annular groove in the inner surface of one of said sections adjacent to the joint between the sections and a circular screen or grid of smaller diameter than the diameter of said recess arranged in said recess, said screen or grid being removable from the casing after the sections have been separated by lifting it into concentric relation to the recess and by subsequent axial movement relatively to the plane of the recess.

4. A strainer of the class described comprising a rigidly supported outlet section, 105 an inlet section having a tubular portion adapted to receive the end of a hose, a screen, and means normally holding the inlet and outlet sections in cooperating engaged relation and for supporting the inlet section 110 when temporarily disengaged from the outlet section.

5. A strainer of the class described comprising an outlet section, an inlet section having a tubular portion to receive the end 115 of a flexible feed pipe, releasable means normally clamping the inlet section to the outlet section, said inlet section having a curved normally inoperative hook, a screen accessible for cleaning when the inlet and outlet sections are separated, and clamping means including a part with which the hook of the inlet section may be engaged, when the sections are separated, for supporting the inlet section, said hook being so shaped as to slip 120 from said part of the clamping means if longitudinal tension is applied to the hose.

6. A strainer of the class described comprising a housing or casing having an inlet section, an outlet section and a removable 130

- screen, the inlet section having a portion shaped for the reception of the end of a flexible hose, means rigidly supporting the outlet section, and means for supporting 5 the inlet section both when operatively engaged with the outlet section and when separated therefrom, said inlet section when uncoupled from the outlet section being capable of disengaging its supporting means if 10 subjected to longitudinal drag of the hose.
7. A strainer comprising a housing or casing having an inlet section and an outlet section, a screen normally held in fixed position between said sections, a rigid support 15 for the outlet section, the inlet section having a tubular portion for the reception of the end of a hose, a clamping device for connecting the sections, and a hook carried by the inlet section and engageable with a part carried 20 by the outlet section temporarily to support the inlet section when the sections are uncoupled, the hook and the part with which it engages being so shaped as to permit the inlet section freely to drop when 25 subjected to pull in a direction away from the outlet section.

8. A strainer comprising a housing or casing having an inlet section and an outlet section, and a screen, a rigid support for the

outlet section, the inlet section being provided with a hose attaching portion, a bail pivotally attached to the outlet section and provided with a clamping bolt engageable with the inlet section normally to connect the sections, and a curved horn projecting 35 from the inlet section engageable with the bail when the sections are uncoupled temporarily to support the inlet section.

9. A strainer comprising a housing or casing having an inlet section and an outlet section, and a removable screen, the inlet section having an externally corrugated tubular part for the reception of a flexible hose, a rigid support for the outlet section, a bail pivotally attached to the outlet section, said bail carrying a pressure applying bolt, the inlet section having a recess and a wear plate within the recess for engagement with the end of the bolt when the parts are assembled, and a hook member carried by 50 the inlet member and engageable with the bail when the inlet and outlet are disconnected whereby temporarily to support the inlet section and the hose connected thereto.

Signed by me at Boston, Massachusetts 55
this 24th day of July 1924.

BELVIN T. WILLISTON.
